UNITED STATES PATENT OFFICE.

ZACARIAH C. PHILLIPS, OF ALLEGHENY CITY, PENNSYLVANIA.

IMPROVEMENT IN BORING-MACHINES.

Specification forming part of Letters Patent No. 122,402, dated January 2, 1872.

To all whom it may concern:

Be it known that I, ZACARIAH C. PHILLIPS, of the city and county of Allegheny and State of Pennsylvania, have invented a new and useful Improvement in Boring-Machines; and I do hereby declare that the following is a full, clear, and exact description thereof, reference being had to the accompanying drawing and to the letters of reference marked thereon.

The nature of my invention consists in a hollow mandrel provided with an adjustable compound crank, a gauge, and screw-threads, and fitted into a pivoted and adjustable bearing, provided with a trigger which causes the mandrel and its auger to become inoperative by the gauge coming in contact with the trigger, the whole being adapted to wood-boring augers and "bits."

To enable others skilled in the art to make and use my invention, I will proceed to describe more fully its construction and operation.

In the accompanying drawing which forms part of my specification, Figure 1 is a side elevation of my improvement in boring-machine. Fig. 2 is a vertical section at line *y* of Fig. 1, and represents the manner of pivoting the bearing to the frame and seat for the operator. Fig. 3 is an enlarged view, in section, of the mandrel bearing and its trigger.

In the accompanying drawing, *A* represents the frame or seat for the operator. *B* represents two curved and slotted arms, which are used for the purpose of holding the bearing *C* in the desired position with relation to the angle or plane of the axis of the mandrel *D* and the auger or "bit" attached to it, and the angle or axis of the hole or opening desired. The bearing *C* is provided with a trigger, consisting of parts *e f* and a spring, *h*, arranged with relation to each other and secured in the bearing, as shown in Fig. 3. The hollow mandrel *D* is provided with screw-threads *k*, a collar or

gauge, *l*, which is held in the desired position on the mandrel *D* by a thumb-screw, *m*. To the upper end of the mandrel *D* is attached a compound crank, consisting of handles *n o* and levers *p r s t*, which levers may be adjusted through the medium of set-screws *u*, and lengthened, as indicated, by the dotted lines *w*. The desired angle is given to the bearing *C* and mandrel *D* through the medium of the slots *v* in the curved arms *B* and the set-screws *x*. The auger is held in position in the mandrel *D* by a pin or set-screw. The frame *A* is constructed of wood, and the bearing *C*, mandrel *D*, trigger-collar, and arms *B* of suitable metal.

The operation of my improved boring-machine is as follows: Having the parts adjusted and arranged as shown in Figs. 1 and 2, the operator turns or revolves the mandrel *D*, which will revolve the auger, and the screw on the end of it will give it the necessary feed. The depth of the boring being gauged by the collar *l*, as soon as it comes in contact with the point 1 of the part *f* of the trigger the point 2 will be thrown up and the point 3 of part *e* will be thrown into the space between the screw-threads *k* by spring *h*, and thereby cause the mandrel *D* and auger attached to it to travel upward. The parts are then reset for boring a second hole.

Having thus described the construction and operation of my improved boring-machine, what I claim as being of my invention, is—

The pivoted bearing *C* provided with a trigger, as shown, and used in combination with the collar *l* and hollow mandrel *D* provided with a compound crank, all constructed and operating substantially as herein described, and for the purpose set forth.

Z. C. PHILLIPS.
